(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is a front perspective view of the shoe of FIGS. 1-3 shown with unclaimed lacing environment;

FIG. 5 is a side view thereof; and,

FIG. 6 is a rear perspective view thereof.

The uneven-length broken line immediately adjacent to the bottom of the lower shaded area defines a bound of the claimed design and forms no part thereof. The even-length broken lines within the shaded area represent stitching and form no part of the claimed design. The uneven-length broken lines depicting the remainder of the shoe show features that form no part of the claimed design.
